United States Patent Office.

JAMES F. WINCHELL, OF SPRINGFIELD, OHIO, ASSIGNOR TO HIMSELF, GEORGE C. STEELE, AND L. A. SIMONS.

Letters Patent No. 84,330, dated November 24, 1868.

IMPROVED ROAD-SCRAPER.

The Schedule referred to in these Letters Patent and making part of the same.

To all whom it may concern:

Be it known that I, JAMES F. WINCHELL, of Springfield, in the county of Clark, and State of Ohio, have invented certain new and useful improvements in Road-Scrapers; and I do hereby declare that the following is a full, clear, and exact description thereof, reference being had to the accompanying drawings, making part of this specification, and to the letters of reference marked thereon, like letters indicating like parts wherever they occur.

To enable others skilled in the art to construct and use my invention, I will proceed to describe it.

My invention consists in a novel construction of a scraper for moving earth, usually denominated a road-scraper, as hereinafter explained.

Figure 1 is a perspective view,

Figure 2, a side elevation, and

Figure 3, a bottom plan view of my improved scraper.

In making my improved device, I construct the scraper proper with a bottom, A, and sides, B, as represented in the drawings, the sides being made circular on their upper and rear edges, as shown in fig. 2.

About midway of the sides, I form a journal, c, by which the body of the scraper is pivoted to a frame, consisting of two side-bars, C, united by a cross-bar, T, and a rod, F, which latter serves as a handle for holding, guiding, and operating the scraper.

To form the bearings or boxes for the journals c, I cut a circular notch in the lower corner of the bars C, and then secure them therein by means of a metal strap, a, which passes around the end of the bar C, and is fastened thereon by a bolt, passing through the bar C and both ends of the strap a, which latter thus serves not only to hold the journals in place, but also to prevent the end of the bar C from splitting or becoming injured.

Upon one of the sides, B, I attach securely an inclined stop, i, near the front, and, near the rear, two similar stops, m and n, set in opposite directions, with a space between these latter, sufficient to receive and hold the end of a lock-bar, D, pivoted to the under side of the bar C, as represented in fig. 3.

A spring, l, is applied to the bar D, in such a manner as to cause it to press inward, and lock against the stops i, or m and n, as the scraper is revolved on its journals, and thus to lock the frame rigidly to the scraper.

The stops m and n may be made separately, and secured by bolts, or they may both be made in one piece, with a notch at the centre, for the bar D to lock into. In either case, they should be made adjustable, by means of a slot or a series of holes, so that the angle of the frame or handle may be adjusted as desired, to adapt it to be used conveniently by persons

of different heights; and they should be set diagonally, or one in advance of the other, on the side-plate B, so as to prevent the possibility of a stone getting between them, and preventing the lock-bar from operating, as might be the case if they were placed directly opposite each other.

A chain or cord, E, is attached, at one end, to one of the bars C, and at its opposite end to the lock-bar D, so that, by pulling on said chain, the lock will be released, and the scraper permitted to turn on its journals, while the frame is held in position.

A bail, G, is attached to the journals, as shown in fig. 3, for attaching the team.

By this construction, it will be seen that I produce a scraper that can be operated with ease and rapidity. The operator can stand erect, and having the long frame for a handle, can raise or depress the front of the scraper with far greater ease and facility than when constructed in the usual manner.

By making the sides on a circle, as shown, it will be seen that the scraper, when turned upside down, as shown in red in fig. 2, as it must be to empty its contents, will roll over as soon as the lock-bar D is released from the stop i, which is simply to hold it in that position while being drawn along empty.

As it thus rolls over, the bar D will automatically lock against the stops m and n, and thus hold the frame rigidly in position, while the scraper is being filled and moved along.

Not only can it be operated with much greater ease and efficiency than the ordinary kind of scraper, but the handles are kept from being soiled, as they need never touch the ground.

Having thus described my invention,

What I claim, is—

1. The pivoted lever D, in combination with the frame, arranged to lock against the stops m, n, and i, and provided with the chain E for operating it, substantially as described.

2. The stops m, n, and i, arranged to operate as described, for the purpose of holding the scraper in the different positions, as set forth.

3. Providing the scraper with the adjustable stops for adjusting the handle at various angles or heights, substantially as and for the purposes set forth.

4. The manner of securing the frame to the scraper, by means of the notch in the corner of the bars C and metal strap a, arranged as described.

JAMES F. WINCHELL.
